W. H. Greenhoff of Philadelphia, Pa.

Letters Patent No. 3801 Dated Augt 1. 1861.

Design for a Hand Stamp.

Be it known that W. H. Greenhoff of the City and County of Philadelphia, and State of Pennsylvania, have invented a novel ornamental Design for a Hand Stamp; and I do hereby declare the following to be a description of the same, reference being had to the accompanying drawing in which my hand stamp is represented by a perspective view.

The form and design of my stamp is shown in the accompanying drawing, and consists of a bell-shaped Body A, supported upon three legs B.B.B and with an upright plunger C, with a cap D at its upper end, the spring E, resting upon the bell-shaped body A and the under side of the cap D.

The body, as has been said, has a flaring outline, or bell shape, and a general cigar form, viewed in elevation.

The legs B.B.B are ellipsoidal in form, having their greatest diameter toward the upper end and tapering down and becoming gradually smaller in appearance.

That I claim as my and desire to secure by Letters Patent is, the design for a Hand Stamp and plunger as shown and described.

Witness,

W. H. Greenhoff,

Hand Stamp.

W. H. Greenhoff,
